(Cl. D58—2)

To all whom it may concern:

Be it known that I, Jeanne Molinari, a citizen of Switzerland, residing at 2 Genferstrasse, Zurich, Switzerland, have invented a new, original, and ornamental Design for Open Mesh Knitted Shoulder Bag, of which the following is a specification, reference being had to the accompanying drawing, forming a part hereof.

The single figure of the drawing is a side elevational view of an open mesh knitted shoulder bag showing my new design. The body of the bag is shown in full lines at the ends thereof, it being understood that the mesh design of the full line disclosure is continued throughout the portion indicated by dotted lines.

I claim:
The ornamental design for an open mesh knitted shoulder bag, as shown and described.
JEANNE MOLINARI.
